[57] CLAIM

The ornamental design for a wall mounted luminaire, as shown and described.

DESCRIPTION

FIG. 1 is a front perspective view of a wall mounted luminaire showing my new design;

FIG. 2 is a front elevational view thereof;

FIG. 3 is a top plan view thereof;

FIG. 4 is a side elevational view thereof;

FIG. 5 is a bottom plan view thereof;

FIG. 6 is a top plan view of a second embodiment of the design;

FIG. 7 is a side elevational view thereof;

FIG. 8 is a bottom plan view thereof;

FIG. 9 is a top plan view of a third embodiment of the design;

FIG. 10 is a side elevational view thereof;

FIG. 11 is a bottom plan view thereof; and,

FIG. 12 is a rear elevational view.

The front and rear configurations shown in FIGS. 2 and 12 are common to the first, second, and third embodiments.
